22-CYANOHYDRINS OF BIS-NOR CHOLEN-AL COMPOUNDS

Raymond L. Pederson, Kalamazoo Township, Kalamazoo County, and Arnold C. Ott, Kalamazoo, Mich., assignors to The Upjohn Company, Kalamazoo, Mich., a corporation of Michigan

No Drawing. Application October 10, 1955
Serial No. 539,672

24 Claims. (Cl. 260—397.3)

The present invention relates to a novel process for the production of 17-ketosteroids and is more particularly concerned with a process of producing 17-ketosteroids selected from the group consisting of 3-oxygenated 17-ketoandrostanes and 17-ketoetiocholanes, the intermediate products 22-cyanohydrins of 3-oxygenated bisnor-17(20)-cholen-22-als and process of production thereof.

The novel process and intermediates may be illustrated by the following equations:

The term bisnor-17(20)-cholen-22-al as used in the specification and claims includes bisnor-17(20)-cholesterol having additional double bonds in positions 1, 4, 5, and the like and are preferably oxygenated in the 3-position that is substituted by hydroxy, acyloxy wherein the acyl group is of a hydrocarbon carboxylic acid containing from one to eight carbon atoms, inclusive, or keto groups.

The term 17-ketoandrostane is used in its generic sense in the description and claims as inclusive of 17-keto-androstanes with or without double bonds in positions 4, or 5 or in additional positions, and preferably oxygenated in the 3-position, that is substituted by hydroxy, acyloxy, suitably wherein the acyl group is of an organic carboxylic acid containing from one to eight carbon atoms and preferably of a hydrocarbon carboxylic acid containing from one to eight carbon atoms, inclusive, or keto groups.

In a similar manner 17-ketoetiocholane is used generically and includes 17-ketoetiocholanes which may have double bonds in positions 6(7), 9(11) or the like and which are preferably oxygenated in position 3, having a 3-hydroxy, acyloxy, as defined above or keto group.

The process of the present invention comprises: treating a bisnor-17(20)-cholen-22-al (I) with hydrogen cyanide or a reagent releasing hydrogen cyanide, for example, an alkali-metal cyanide, a cyanohydrin of a lower-membered ketone in the presence of an acid to obtain

2

the corresponding 22-cyanohydrin of the selected bisnor-17(20)-cholen-22-al and ozonolysing (i. e., treat with ozone at low temperature to obtain an ozonide and decompose the ozonide thus produced, usually by zinc and acetic acid) the thus prepared cyanohydrin of the 17(20)-bisnorcholesterol-22-al (II) to obtain the corresponding 17-ketoandrostane or 17-ketoetiocholane (III).

It is an object of the present invention to provide an improved method for the production of 17-ketosteroids of the androstane and etiocholane series from the corresponding 17(20)-bisnorcholesterol aldehydes, through selective cyanohydrin formation and selective ozonolysis of the 17(20)-double bond. It is another object of the instant invention to produce useful steroid intermediates belonging to the class of 22-cyanohydrins of bisnor-17(20)-cholen-22-als without addition of hydrogen cyanide to double bonds or keto groups. Another object of the instant invention is the provision of a process for the production of the 22-cyanohydrins of bisnor-17(20)-cholen-22-als, especially the 22-cyanohydrins of 3-ketobisnor-4,17(20)-cholen-22-als, 3-ketobisnor-17(20)-bisnorcholesterol-22-als, 3-hydroxy- and 3-acyloxybisnor-5,17(20)-cholen-22-als wherein the acyl group is defined as before, and the 6- and 11-hydroxy, acyloxy and keto derivatives thereof, by a selective cyanohydrin formation process. Other objects of the present invention will be apparent to those skilled in the art to which this invention pertains.

The intermediates and the process of the present invention are useful for the production of physiologically active compounds and key-intermediates for the production of such physiologically active compounds. Thus from the cyanohydrin of 3-ketobisnor-4,17(20)-cholen-22-als, through ozonolysis is obtained 4-androstene-3,17-dione possessing androgenic properties and being an intermediate in the production of testosterone; 3,11-diketobisnor-4,17(20)-cholen-22-als through its cyanohydrin is useful for the production of androgenic and anabolic active adrenosterone; similarly: 3 α - or 3 β -hydroxybisnor-17(20)-cholen-22-als give anesthetically active 3 α - or 3 β -hydroxyetiocholane-17-ones, 3,11-diketobisnor-17(20)-cholen-22-als gives etiocholane-3,11,17-trione (general anesthetic activity), 3-hydroxy- or 3-acyloxy-6-ketobisnor-cholen-22-als provide the corresponding 3-hydroxyetiocholane-6,17-dione and 3-esters thereof which can be oxidized (in case of a 3-ester after hydrolysis) to the corresponding etiocholane-3,6,17-trione (which may be brominated to 4-bromoetiocholane-3,6,17-trione and dehydrobrominated to give 4-androstene-3,6,17-trione of estrogenic activity). Similarly etiocholane-3,6,17-trione may also be prepared from 3,6-diketobisnor-17(20)-cholen-21-als 21-cyanohydrin. 3,11-allobisnor-17(20)-cholen-22-als 22-cyanohydrin yields androgenically active androstan-3,11,17-trione. The cyanohydrins of such 17(20)-bisnorcholesterolaldehydes are ozonized and give higher yields of 17-ketosteroids than the ozonolysis of the free 17(20)-bisnorcholesterolaldehydes.

The starting compounds of the present invention are bisnor-17(20)-cholen-22-als, such as: bisnor-17(20)-cholen-22-als, bisnor-4,17(20)-cholen-22-als, 3-ketobisnor-17(20)-cholen-22-als, 3-ketobisnor-4,17(20)-cholen-22-als, 3-hydroxybisnor-17(20)-cholen-22-als, 3 α - and 3 β -acetoxybisnor-17(20)-cholen-22-als, 3 α - and 3 β -hydroxybisnor-5,17(20)-cholen-22-als, 3 α - and 3 β -acetoxybisnor-5,17(20)-cholen-22-als, 3,11-diketobisnor-4,17(20)-cholen-22-als, 3-ketoallobisnor-17(20)-cholen-22-als, 3,11-diketoallobisnor-17(20)-cholen-22-als, 3,6-diketobisnor-17(20)-cholen-22-als, 3-ketobisnor-11 α -hydroxy- and 3-ketobisnor-11 β -hydroxy-4,17(20)-cholen-22-als, 3 β -hydroxy- and 3 β -acetoxy-6-ketobisnor-17(20)-cholen-22-als, 3-ketobisnor-17(20)-cholen-22-als, 3,11-dihydroxybisnor-17(20)-cholen-22-als, 3,12-dihy-

droxybisnor-17(20)-cholen-22-al, 3-acyloxybisnor-17(20)-cholen-22-al, 3-acyloxybisnor-5,17(20)-choladien-22-al, 3-acyloxy-6-ketobisnor-17(20)-cholen-22-al, 3-acyl-oxbisnorrallo-17(20)-cholen-22-al, 3-ketobisnor-11 α -acyloxy-4,17(20)-choladien-22-al, 3,11-diacyloxybisnor-17(20)-cholen-22-al, 3,12-diacyloxybisnor-17(20)-cholen-22-al, and the like, wherein the acyloxy group is of an organic carboxylic acid containing from one to eight carbon atoms, inclusive, preferably of a hydrocarbon carboxylic acid containing from one to eight carbon atoms, inclusive. Representative acyloxy groups illustratively comprise: formyloxy, acetoxy, propionyloxy, butyryloxy, isobutyryloxy, valeryloxy, isovaleryloxy, hexanoxyloxy, heptanoxyloxy, octanoxyloxy, benzoxyloxy, (β -cyclopentylpropionyloxy), dimethylacetoxyl, trimethylacetoxyl, phenylacetoxyl, toluylloxy, anisoyloxy, gallxyloxy, salicyloyloxy, cinnamylloxy, hemisuccinylloxy, hemitartrylloxy, dihydrogencitryloxy, hemimaleylloxy, hemifumarylloxy, crotonyloxy, acrylyloxy, β -methylcrotonyloxy, cyclohexanecarbonyloxy, chloroacetoxyl, dichloroacetoxyl, trichloroacetoxyl, bromoacetoxyl, hemiquinolinoloyloxy, nicotinylloxy, piperonyloxy, 2-furoyloxy, thioglycolyloxy, para-chlorobenzoyloxy, para-bromobenzoyloxy, meta-nitrobenzoyloxy, (3,5-dinitrobenzoyloxy), benzenesulfonyloxy, para-chlorobenzenesulfonyloxy, para-toluene-sulfonyloxy, para-nitrobenzenesulfonyloxy, 3,5-dinitrobenzenesulfonyloxy, benzenephosphonyloxy, and the like.

The preparation of the starting compounds belonging to the new class of bisnor-17(20)-cholen-22-als is described in detail in copending application Serial No. 539,671, filed October 10, 1955, and comprises: reacting a bisnorcholan aldehyde, either available or produced by reduction of the carboxyl group of the known bisnorcholanic acid to an aldehyde group by methods known in the art [Rosenmund, McFayden-Stevens and the more recent method by Weygand et al., Angew. Chem. 65, 525 (1953)], with a secondary amine, preferably a cyclic secondary amine such as piperidine, morpholine, pyrrolidine, homomorpholine, and the like, to obtain the corresponding 22-(N-tertiaryaminobisnor)-20(22)-cholen, brominating the thus obtained 22-(N-tertiaryaminobisnor)-20(22)-cholen at a temperature between about minus thirty and plus twenty degrees centigrade to obtain a 20-bromobisnorcholan-22-al and dehydrobrominating with pyridine or other tertiary amines to obtain the corresponding bisnor-17(20)-cholen-22-al.

In carrying out the process of the present invention the selected bisnor-17(20)-cholen-22-al, slurried or dissolved in a suitable organic solvent such as methanol, ethanol, dioxane, acetone, tertiary butyl alcohol with methanol or ethanol preferred, is reacted with hydrogen cyanide. The hydrogen cyanide may be suitably introduced as a gas into the solution of the bisnor-17(20)-cholen-22-al from a hydrogen cyanide containing gas cylinder or from a hydrogen cyanide producing apparatus, or the hydrogen cyanide may be developed in situ in the reaction vessel by causing an alkali metal cyanide, or a lower keto or aldehyde cyanohydrin, such as acetone cyanohydrin to react with a dilute acid. In the preferred embodiment of the invention the hydrogen cyanide is produced in situ by adding an alkali metal cyanide such as sodium or potassium cyanide to the solution of the bisnor-17(20)-cholen-22-al and dropwise thereafter an acid. Strong acid is unnecessary to liberate hydrogen cyanide; organic acids with a melting point lower than zero degrees, preferably lower than fifty degrees centigrade, especially hydrocarbon carboxylic acids such as formic, acetic, propionic, butyric, or the like, or dilute aqueous mineral acids, such as five to ten percent sulfuric, chloric, perchloric acid or the like, are generally employed with acetic acid preferred. Other metal cyanides may be used instead of the sodium or potassium cyanide, such as lithium cyanide, calcium cyanide, barium cyanide, or the like. In the preferred in situ preparation of the hydrogen cyanide gas the rate of addition of the acid is

controlled; furthermore the reaction speed is decreased by cooling the reaction mixture to a temperature between minus fifty to zero degrees centigrade. After the reaction is completed the 22-cyanohydrin of the bisnor-17(20)-cholen-22-al is recovered from the reaction mixture by conventional means preferably by extraction with a water immiscible solvent, such as ether, methylene chloride, chloroform, carbon tetrachloride, benzene, and the like. In order to obtain the solid 22-cyanohydrin of bisnor-17(20)-cholen-22-al the extracts are concentrated until the solid product precipitates. Purification is effected by recrystallization from organic solvents such as ether, methanol, ethanol, dioxane, or the like.

For the purpose of obtaining a 17-ketosteroid selected from 17-ketoandrostanes and 17-ketoetiocholanes, the cyanohydrin of the bisnor-17(20)-cholen-22-al is submitted to ozonolysis. For ozonolysis it is not necessary that the cyanohydrin of the bisnor-17(20)-cholen-22-al be isolated, in its stead the solution resulting from the extraction of the reaction mixture can be used. In the preferred embodiment of the instant invention the methylene chloride or chloroform solution resulting from the extraction of the before-mentioned reaction mixture is concentrated to approximately one millimole of the cyanohydrin of the steroid per ten milliliters of solution. Smaller or greater concentration of steroid cyanohydrin may also be used. The thus obtained solution is then cooled to a temperature between minus forty to minus ninety degrees and ozonized with a mixture of ozone-oxygen. The thus obtained ozonide is decomposed in the usual manner with zinc dust and the acetic acid. Stirring is preferred during the decomposition of the ozonide. The product, a 17-ketosteroid, is recovered by conventional means, such as removal of the zinc by filtration and concentrating the reaction mixture to dryness in vacuo.

The thus obtained ketosteroid is purified by conventional procedures, preferably by recrystallization from suitable solvents such as ether, methanol, ethanol, acetone, Skellysolve B hexanes, benzene, and the like.

The following examples are illustrative of the process and products of the present invention but are not to be construed as limiting.

EXAMPLE 1

Cyanohydrin of 3-ketobisnor-4,17(20)-choladien-22-al

A slurry consisting of 8.16 grams (25 millimoles) of 3-keto-bisnor-4,17(20)-choladien-22-al of melting point 124 to 133 degrees centigrade, 12.3 grams (250 millimoles) of sodium cyanide and 75 milliliters of anhydrous methanol was cooled to minus twenty degrees centigrade and thereto was added under continuous rapid stirring 11.5 milliliters (200 millimoles) of glacial acetic acid during a period of one hour. The mixture during the dropwise addition became very thick and the temperature increased to zero degrees centigrade. Thereafter the reaction mixture was placed in a refrigerator and kept at a temperature between zero and five degrees centigrade for a period of 48 hours. The thus obtained thick paste was shaken with 300-milliliters of ice cold methylene chloride. The resulting mixture was washed with 150-milliliter portions, then with four fifty-milliliter portions of ice water. The methylene chloride solution was dried with ten grams of anhydrous sodium sulfate during a period of eighteen hours at a temperature of zero to five degrees centigrade. The mixture thereupon was filtered and concentrated to 250 milliliters at a temperature of 20 to 25 degrees centigrade and under partially reduced pressure. This solution was ready for the ozonolysis described in Example 2.

Evaporation to dryness of such a solution yielded an amorphous solid which upon recrystallization from absolute ether gave fine white crystals of melting point 75 178 to 183 degrees centigrade (decomposition).

Analysis.—Calcd. for $C_{23}H_{31}NO_2$: C, 78.14; H, 8.84; N, 3.96. Found: C, 78.20; H, 9.30; N, 4.15.

$\lambda_{\text{max}}^{\text{ether}}$ 282.5 m μ , E 17,150

$\lambda_{\text{max}}^{\text{Nujol}}$ 3360 cm. $^{-1}$ (OH), 1660 cm. $^{-1}$ (conj. C=O)

EXAMPLE 2

4-androstene-3,17-dione

The 250 milliliters of methylene chloride solution containing theoretically 25 millimoles of the monocyanohydrin of 3-ketobisnor-4,17(20)-choladien-22-al of Example 1, was cooled to about minus seventy degrees centigrade. To this solution was added 2.4 milliliters of anhydrous pyridine and the solution was ozonized with an ozone-oxygen stream producing 0.405 millimole of ozone per minute for a period of 75 minutes. During the last three minutes ozone passed into the overflow trap. The absorption of ozone was 29.4 millimoles or 1.18 moles per mole of steroid. The cold ozonized solution was thereupon quickly transferred to a flask equipped with a stirrer, and fifty milliliters of acetic acid was added in one portion, followed immediately by five grams of zinc dust. The mixture was then stirred rapidly for a period of two hours, during which time it reached room temperature. Thereafter the reaction mixture was filtered and diluted with 250 milliliters of Skellysolve A hexanes. It was thereupon washed with 100 milliliters of water, then two 50-milliliter portions of water, two 150-milliliter portions of ten percent sodium hydroxide solution, fifty milliliters of water, fifty milliliters of ten percent hydrochloric acid solution and two 50-milliliter portions of water. Thereafter the solution was dried overnight with anhydrous sodium sulfate at a temperature between zero and five degrees, then filtered and concentrated to dryness in vacuo. The last traces of solvent were removed at sixty degrees centigrade at a pressure of twenty to thirty milliliter mercury leaving 6.55 grams (91.4 percent yield) of white crystals of melting point 155 to 160 degrees of 4-androstene-3,17-dione. (4-androstene-3,17-dione has two crystal forms: one melting at 142 to 144 degrees centigrade, the other at 173 to 174 degrees centigrade.)

EXAMPLE 3

22-cyanohydrin of 3 α -acetoxybisnor-17(20)-cholen-22-al

In the same manner as Example 1, a solution of 3 α -acetoxybisnor-17(20)-cholen-22-al in ethanol was treated with potassium cyanide and ten percent hydrochloric acid. The thus obtained chlorohydrin of 3 α -acetoxybisnor-17(20)-cholen-22-al was separated from the reaction mixture by extraction with chloroform, the chloroform solution was dried over anhydrous sodium sulfate, and evaporated to give white crystals which were purified by recrystallization from ethyl acetate-Skellysolve B hexanes to give pure cyanohydrin of 3 α -acetoxybisnor-17(20)-cholen-22-al.

EXAMPLE 4

3 α -acetoxyetiocholan-17-one

In the manner given in Example 2, 3 α -acetoxybisnor-17(20)-cholen-22-al was subjected to ozonolysis, while dissolved in methylene dichloride, to give 3 α -acetoxyetiocholan-17-one.

EXAMPLE 5

22-cyanohydrin of 3,11-diketobisnor-4,17(20)-choladien-22-al

In the manner given in Example 1, reacting 3,11-diketobisnor-4,17(20)-choladien-22-al, dissolved in methanol, with sodium cyanide and acetic acid yielded the 22-cyanohydrin of 3,11-diketobisnor-4,17(20)-choladien-22-al.

EXAMPLE 6

4-androstene-3,11,17-trione (adrenosterone)

Ozonolyzing in the manner shown in Example 2, the 22-cyanohydrin of 3,11-diketobisnor-4,17(20)-choladien-22-al produced 4-androstene-3,11,17-trione (adrenosterone).

EXAMPLE 7

22-cyanohydrin of 3 β -acetoxy-6-ketobisnor-17(20)-cholen-22-al

In the manner given in Example 1, reacting 3 β -acetoxy-6-ketobisnor-17(20)-cholen-22-al, dissolved in methanol, with sodium cyanide and acetic acid, yielded the 22-cyanohydrin of 3 β -acetoxy-6-ketobisnor-17(20)-cholen-22-al.

EXAMPLE 8

3 β -acetoxyetiocholan-6,17-dione

Ozonolyzing in the manner shown in Example 2, the 22-cyanohydrin of 3 β -acetoxy-6-ketobisnor-17(20)-cholen-22-al produced 3 β -acetoxyetiocholan-6,17-dione.

EXAMPLE 9

22-cyanohydrin of 3,6-diketobisnor-17(20)-cholen-22-al

In the manner given in Example 1, reacting 3,6-diketobisnor-17(20)-cholen-22-al, dissolved in methanol, with sodium cyanide and acetic acid, yielded the 22-cyanohydrin of 3,6-diketobisnor-17(20)-cholen-22-al.

EXAMPLE 10

Etiocholane-3,6,17-trione

Ozonolyzing in the manner shown in Example 2, the 22-cyanohydrin of 3,6-diketobisnor-17(20)-cholen-22-al produced etiocholan-3,6,17-trione.

EXAMPLE 11

22-cyanohydrin of 3-ketoallobisnor-17(20)-cholen-22-al

In the manner given in Example 1, reacting 3-ketoallobisnor-17(20)-cholen-22-al, dissolved in methanol, with sodium cyanide and acetic acid, yielded the 22-cyanohydrin of 3-ketoallobisnor-17(20)-cholen-22-al.

EXAMPLE 12

Androstane-3,17-dione

Ozonolyzing in the manner shown in Example 2, the 22-cyanohydrin of 3-ketoallobisnor-17(20)-cholen-22-al produced androstane-3,17-dione.

EXAMPLE 13

22-cyanohydrin of 3 α -hydroxybisnor-5,17(20)-choladien-22-al

In the manner given in Example 1, reacting 3 α -hydroxybisnor-5,17(20)-choladien-22-al, dissolved in methanol, with sodium cyanide and acetic acid, yielded the 22-cyanohydrin of 3 α -hydroxybisnor-5,17(20)-choladien-22-al.

EXAMPLE 14

3 α -hydroxy-5-androsten-17-one

Ozonolyzing in the manner shown in Example 2, the 22-cyanohydrin of 3 α -hydroxybisnor-5,17(20)-choladien-22-al produced 3 α -hydroxy-5-androsten-17-one.

EXAMPLE 15

22-cyanohydrin of 3 α -hydroxyallobisnor-17(20)-cholen-22-al

In the manner given in Example 1, reacting 3 α -hydroxyallobisnor-17(20)-cholen-22-al, dissolved in methanol, with sodium cyanide and acetic acid, yielded the 22-cyanohydrin of 3 α -hydroxyallobisnor-17(20)-cholen-22-al.

EXAMPLE 16

3 α -hydroxyandrostan-17-one

Ozonolyzing in the manner shown in Example 2, the 22-cyanohydrin of 3α -hydroxyallobisnor-17(20)-cholen-22-al produced 3α -hydroxyandrostan-17-one.

EXAMPLE 17

22-cyanohydrin of 3 α -acetoxyallobisnor-17(20)-cholen-22-al

In the manner given in Example 1, reacting 3α -acetoxyallobisnor-17(20)-cholen-22-al, dissolved in methanol, with sodium cyanide and acetic acid, yielded the 22-cyanohydrin of 3α -acetoxyallobisnor-17(20)-cholen-22-al.

EXAMPLE 18

3 α -acetoxyandrostan-17-one

Ozonolyzing in the manner shown in Example 2, the 22-cyanohydrin of 3α -acetoxyallobisnor-17(20)-cholen-22-al produced 3α -acetoxyandrostan-17-one.

EXAMPLE 19

22-cyanohydrin of 3,11-diketobisnor-17(20)-cholen-22-al

In the manner given in Example 1, reacting 3,11-diketobisnor-17(20)-cholen-22-al, dissolved in methanol, with sodium cyanide and acetic acid, yielded the 22-cyanohydrin of 3,11-diketobisnor-17(20)-cholen-22-al.

EXAMPLE 20

Etiocholane-3,11,17-trione

Ozonolyzing in the manner shown in Example 2, the 22-cyanohydrin of 3,11-diketobisnor-17(20)-cholen-22-al produced etiocholane-3,11,17-trione.

EXAMPLE 21

22-cyanohydrin of 3-ketobisnor-11 α -hydroxy-17(20)-cholen-22-al

In the manner given in Example 1, reacting 3-ketobisnor-11 α -hydroxy-17(20)-cholen-22-al, dissolved in methanol, with sodium cyanide and acetic acid, yielded the 22-cyanohydrin of 3-ketobisnor-11 α -hydroxy-17(20)-cholen-22-al.

EXAMPLE 22

11 α -hydroxyetiocholane-3,17-dione

Ozonolyzing in the manner shown in Example 2, the 22-cyanohydrin of 3-ketobisnor-11 α -hydroxy-17(20)-cholen-22-al produced 11 α -hydroxyetiocholane-3,17-dione.

EXAMPLE 23

22-cyanohydrin of 3-ketobisnor-11 β -hydroxy-17(20)-cholen-22-al

In the manner given in Example 1, reacting 3-ketobisnor-11 β -hydroxy-17(20)-cholen-22-al, dissolved in methanol, with sodium cyanide and acetic acid, yielded the 22-cyanohydrin of 3-ketobisnor-11 β -hydroxy-17(20)-cholen-22-al.

EXAMPLE 24

11 β -hydroxyetiocholane-3,17-dione

Ozonolyzing in the manner shown in Example 2, the 22-cyanohydrin of 3-ketobisnor-11 β -hydroxy-17(20)-cholen-22-al produced 11 β -hydroxyetiocholane-3,17-dione.

EXAMPLE 25

22-cyanohydrin of 3,11-diketoallobisnor-17(20)-cholen-22-al

In the manner given in Example 1, reacting 3,11-diketoallobisnor-17(20)-cholen-22-al, dissolved in methanol, with sodium cyanide and acetic acid, yielded the 22-cyanohydrin of 3,11-diketoallobisnor-17(20)-cholen-22-al.

EXAMPLE 26

Androstane-3,11,17-trione

Ozonolyzing in the manner shown in Example 2, the 22-cyanohydrin of 3,11-diketoallobisnor-17(20)-cholen-22-al produced androstane-3,11,17-trione.

In the same manner as Example 1, other cyanohydrins may be produced, such as illustratively the 22-cyanohydrins of 3-ketobisnor-11 α -hydroxy-4,17(20)-choladien-22-al, 3-ketobisnor-6 β ,11 α -dihydroxy-4,17(20)-choladien-22-al, 3,6-diketoallobisnor-11 α -acetoxy-17(20)-cholen-22-al, 3-ketobisnor-6 β ,11 α -dipropionyloxy-4,17(20)-choladien-22-al, 3,12-diketobisnor-4,17(20)-choladien-22-al, 3,7-diketoallobisnor-17(20)-cholen-22-al, and the like.

These 22-cyanohydrins can be subjected to ozonolysis in the manner shown in Example 2 to give respectively 11 α -hydroxy-4-androstene-3,17-dione, 6 β ,11 α -dihydroxy-4-androstene-3,17-dione, 11 α -acetoxyandrostane-3,6-dione, 11 β -hydroxyandrostane-3,17-dione, 6 β ,11 α -dipropionyloxy-4-androstene-3,17-dione, 4-androstene-3,12,17-trione, androstane-3,7,17-trione, and the like.

It is to be understood that the invention is not to be limited to the exact details of operation or exact compounds shown and described, as obvious modifications and equivalents will be apparent to one skilled in the art, and the invention is therefore to be limited only by the scope of the appended claims.

We claim:

- 30 1. The 22-cyanohydrin of a bisnor-17(20)-cholen-22-al substituted in the 3-position by a group selected from hydroxy, acyloxy wherein the acyl group is of a hydrocarbon carboxylic acid containing from one to eight carbon atoms, inclusive, and keto.
- 35 2. The 22-cyanohydrin of a 3-ketobisnor-17(20)-cholen-22-al.
  3. 22-cyanohydrin of 3-ketobisnor-4,17(20)-choladien-22-al.
  4. 22-cyanohydrin of 3,11-diketobisnor-4,17(20)-choladien-22-al.
- 40 5. 22-cyanohydrin of 3,6-diketobisnor-17(20)-cholen-22-al.
  6. The 22-cyanohydrin of a allobisnor-17(20)-cholen-22-al substituted in the 3-position by a group selected from hydroxy, acyloxy wherein the acyl group is of a hydrocarbon carboxylic acid containing from one to eight carbon atoms, inclusive, and keto.
  7. 22-cyanohydrin of 3-ketoallobisnor-17(20)-cholen-22-al.
- 45 8. The 22-cyanohydrin of a 3-acyloxybisnor-17(20)-cholen-22-al, wherein the acyl group is of a hydrocarbon carboxylic acid containing from one to eight carbon atoms, inclusive.
  9. 22-cyanohydrin of 3 α -acetoxybisnor-17(20)-cholen-22-al.
- 55 10. A process for the production of a 22-cyanohydrin of a 3-oxygenated bisnor-17(20)-cholen-22-al which comprises: reacting a 3-oxygenated bisnor-17(20)-cholen-22-al wherein the 3-oxygenated group is selected from the class consisting of hydroxy, acyloxy, wherein the acyl group is of an organic carboxylic acid containing from one to eight carbon atoms, inclusive, and keto, with hydrogen cyanide to obtain the cyanohydrin of the corresponding 3-oxygenated bisnor-17(20)-cholen-22-al.
  11. A process for the production of a 22-cyanohydrin of a 3-oxygenated bisnor-17(20)-cholen-22-al which comprises: adding, to a mixture of a 3-oxygenated bisnor-17(20)-cholen-22-al wherein the 3-oxygenated group is selected from the class consisting of hydroxy, acyloxy, wherein the acyl group is of an organic carboxylic acid containing from one to eight carbon atoms, inclusive, and keto and an alkali-metal cyanide in an organic solvent, an acid selected from the group consisting of organic carboxylic acids of low melting point and dilute aqueous
- 60 12. A process for the production of a 22-cyanohydrin of a 3-oxygenated bisnor-17(20)-cholen-22-al which comprises: adding, to a mixture of a 3-oxygenated bisnor-17(20)-cholen-22-al wherein the 3-oxygenated group is selected from the class consisting of hydroxy, acyloxy, wherein the acyl group is of an organic carboxylic acid containing from one to eight carbon atoms, inclusive, and keto and an alkali-metal cyanide in an organic solvent, an acid selected from the group consisting of organic carboxylic acids of low melting point and dilute aqueous
- 65 13. A process for the production of a 22-cyanohydrin of a 3-oxygenated bisnor-17(20)-cholen-22-al which comprises: adding, to a mixture of a 3-oxygenated bisnor-17(20)-cholen-22-al wherein the 3-oxygenated group is selected from the class consisting of hydroxy, acyloxy, wherein the acyl group is of an organic carboxylic acid containing from one to eight carbon atoms, inclusive, and keto and an alkali-metal cyanide in an organic solvent, an acid selected from the group consisting of organic carboxylic acids of low melting point and dilute aqueous
- 70 14. A process for the production of a 22-cyanohydrin of a 3-oxygenated bisnor-17(20)-cholen-22-al which comprises: adding, to a mixture of a 3-oxygenated bisnor-17(20)-cholen-22-al wherein the 3-oxygenated group is selected from the class consisting of hydroxy, acyloxy, wherein the acyl group is of an organic carboxylic acid containing from one to eight carbon atoms, inclusive, and keto and an alkali-metal cyanide in an organic solvent, an acid selected from the group consisting of organic carboxylic acids of low melting point and dilute aqueous
- 75 15. A process for the production of a 22-cyanohydrin of a 3-oxygenated bisnor-17(20)-cholen-22-al which comprises: adding, to a mixture of a 3-oxygenated bisnor-17(20)-cholen-22-al wherein the 3-oxygenated group is selected from the class consisting of hydroxy, acyloxy, wherein the acyl group is of an organic carboxylic acid containing from one to eight carbon atoms, inclusive, and keto and an alkali-metal cyanide in an organic solvent, an acid selected from the group consisting of organic carboxylic acids of low melting point and dilute aqueous

mineral acids to obtain the 22-cyanohydrin of the 3-oxygenated bisnor-17(20)-cholen-22-al.

12. A process for the production of a 22-cyanohydrin of a 3-ketobisnor-17(20)-cholen-22-al which comprises: adding, to a mixture of a 3-ketobisnor-17(20)-cholen-22-al and an alkali-metal cyanide in an organic solvent, an acid selected from the group consisting of organic carboxylic acids of low melting point and dilute aqueous mineral acids to obtain the 22-cyanohydrin of the 3-ketobisnor-17(20)-cholen-22-al.

13. A process for the production of the 22-cyanohydrin of 3-ketobisnor-4,17(20)-choladien-22-al which comprises: adding acetic acid at a temperature between about minus fifty and zero degrees centigrade to a mixture of 3-ketobisnor-4,17(20)-choladien-22-al and an alkali-metal cyanide in an organic solvent to obtain the 22-cyanohydrin of 3-ketobisnor-4,17(20)-choladien-22-al.

14. A process for the production of the 22-cyanohydrin of 3,11-diketobisnor-4,17(20)-choladien-22-al which comprises: adding acetic acid at a temperature between about minus fifty and about zero degrees centigrade to a mixture of 3,11-diketobisnor-4,17(20)-choladien-22-al and an alkali-metal cyanide in an organic solvent to obtain the 22-cyanohydrin of 3,11-diketobisnor-4,17(20)-choladien-22-al.

15. A process for the production of the 22-cyanohydrin of 3,6-diketobisnor-17(20)-cholen-22-al which comprises: adding acetic acid at a temperature between about minus fifty and about zero degrees centigrade to a mixture of 3,6-diketobisnor-4,17(20)-choladien-22-al and an alkali-metal cyanide in an organic solvent to obtain the 22-cyanohydrin of 3,6-diketobisnor-17(20)-cholen-22-al.

16. A process for the production of the 22-cyanohydrin of 3-ketoallobisnor-17(20)-cholen-22-al which comprises: adding acetic acid at a temperature between about minus fifty and about zero degrees centigrade to a mixture of 3-ketoallobisnor-17(20)-cholen-22-al and an alkali-metal cyanide in an organic solvent to obtain the 22-cyanohydrin of 3-ketoallobisnor-17(20)-cholen-22-al.

17. A process for the production of the 22-cyanohydrin of 3 α -acetoxybisnor-17(20)-cholen-22-al which comprises: adding acetic acid at a temperature between about minus fifty and about zero degrees centigrade to a mixture of 3 α -acetoxybisnor-17(20)-cholen-22-al and an alkali-metal cyanide in an organic solvent to obtain the 22-cyanohydrin of 3 α -acetoxybisnor-17(20)-cholen-22-al.

18. A process for the production of a 3-oxygenated 17-ketosteroid selected from the group consisting of 17-ketoandrostanes and 17-ketoetiocholanes, which comprises: reacting a 3-oxygenated bisnor-17(20)-cholen-22-al wherein the 3-oxygenated group is selected from the class consisting of hydroxy, acyloxy wherein the acyl group is of an organic carboxylic acid containing from one to eight carbon atoms, inclusive, and keto with hydrogen cyanide to obtain the cyanohydrin of the corresponding 3-oxygenated bisnor-17(20)-cholen-22-al and subjecting the thus obtained cyanohydrin to ozonolysis to obtain the corresponding 3-oxygenated 17-ketosteroid.

19. A process for the production of a 3-oxygenated 17-ketosteroid selected from the group consisting of 17-ketoandrostanes and 17-ketoetiocholanes, which comprises: adding, to a mixture of a 3-oxygenated bisnor-

17(20)-cholen-22-al wherein the 3-oxygenated group is selected from the class consisting of hydroxy, acyloxy, wherein the acyl group is of an organic carboxylic acid containing from one to eight carbon atoms, inclusive, and keto and an alkali-metal cyanide in an organic solvent, an acid selected from the group consisting of organic carboxylic acids of low melting point and dilute aqueous mineral acid to obtain the 22-cyanohydrin of the 3-oxygenated bisnor-17(20)-cholen-22-al, and subjecting the thus obtained 3-oxygenated bisnor-17(20)-cholen-22-al 22-cyanohydrin to ozonolysis to obtain the corresponding 3-oxygenated 17-ketosteroid.

20. A process for the production of 4-androstene-3,17-dione which comprises: adding acetic acid at a temperature between about minus fifty and about zero degrees centigrade to a mixture of 3-ketobisnor-4,17(20)-choladien-22-al and an alkali-metal cyanide in an organic solvent to obtain the cyanohydrin of 3-ketobisnor-4,17(20)-choladien-22-al and submitting the thus obtained 3-ketobisnor-4,17(20)-choladien-22-al 22-cyanohydrin to ozonolysis to obtain 4-androstene-3,17-dione.

21. A process for the production of adrenosterone which comprises: adding acetic acid at a temperature between about minus fifty and about zero degrees centigrade to a mixture of 3,11-diketobisnor-4,17(20)-choladien-22-al and an alkali-metal cyanide in an organic solvent to obtain the 22-cyanohydrin of 3,11-diketobisnor-4,17(20)-choladien-22-al and submitting the thus obtained 3,11-diketobisnor-4,17(20)-choladien-22-al 22-cyanohydrin to ozonolysis to obtain adrenosterone.

22. A process for the production of etiocholan-3,6,17-trione which comprises: adding acetic acid at a temperature between minus fifty and about zero degrees centigrade to a mixture of 3,6-diketobisnor-17(20)-cholen-22-al and an alkali-metal cyanide in an organic solvent to obtain 3,6-diketobisnor-17(20)-cholen-22-al 22-cyanohydrin and subjecting the thus produced 3,6-diketobisnor-17(20)-cholen-22-al 22-cyanohydrin to ozonolysis to obtain etiocholan-3,6,17-trione.

23. A process for the production of androstane-3,17-dione which comprises: adding acetic acid at a temperature between about minus fifty and about zero degrees centigrade to a mixture of 3-ketoallobisnor-17(20)-cholen-22-al and an alkali-metal cyanide in an organic solvent to obtain the 22-cyanohydrin of 3-ketoallobisnor-17(20)-cholen-22-al and subjecting the thus obtained 3-ketoallobisnor-17(20)-cholen-22-al 22-cyanohydrin to ozonolysis to obtain androstane-3,17-dione.

24. A process for the production of 3 α -acetoxyetiocholan-17-one which comprises: adding acetic acid at a temperature between about minus fifty and about zero degrees centigrade to a mixture of 3 α -acetoxybisnor-17(20)-cholen-22-al and an alkali-metal cyanide in an organic solvent to obtain the 22-cyanohydrin of 3 α -acetoxybisnor-17(20)-cholen-22-al and subjecting the thus obtained 3 α -acetoxybisnor-17(20)-cholen-22-al 22-cyanohydrin to ozonolysis to obtain 3 α -acetoxyetiocholan-17-one.
